DRAFTING MECHANISM

Edward L. Martin, Providence, and John Frederick Jackson, Pawtucket, R. I., assignors to H & B American Machine Company, a corporation of Maine

Application May 11, 1936, Serial No. 79,059

7 Claims. (Cl. 19—131)

This invention relates to an apparatus for attenuating fibrous material, more particularly for the formation of thread or yarn; and has for one of its objects the provision of an endless belt or apron for conducting the work from one pair of nipping elements to another with the parts so arranged that the apron or endless belt may be operatively positioned by a simple maneuver while maintaining the belt in endless condition.

Another object of the invention is to provide a drafting mechanism of the belt or apron type in which one or more belts may be removed and replaced quickly by stopping only the respective spindles affected by the individual belts thereby obviating any shut-down of the complete machine with the consequent loss of production and expense which has heretofore been the case during use of the prior art cemented belt devices.

Another object of the invention is to enable a drafting apparatus to be used immediately after a new belt is assembled on a frame rather than waiting for the cement to dry, as has previously been necessary with the cemented belts.

Another object of the invention is the driving of a belt in a drafting mechanism of this character at two distinct points and the provision of a pull as well as a push on the belt along the work engaging portion of its surface while leaving the inactive portion of the belt untensioned and merely guided in its path of travel.

Another object of the invention is to so position the belt of a belt or apron drafting apparatus that when the work is fed to the back nipping elements it will fall onto the belt and be fed to the middle pair of nipping elements without manual handling.

Another object of the invention is the positive driving of the lower roll which is embraced by the belt by engagement with a driving member which extends for a considerable distance lengthwise of the frame.

With these and other objects in view, the invention consists of certain novel features of construction, as will be more fully described, and particularly pointed out in the appended claims.

In the accompanying drawings:

Fig. 1 is a sectional view looking at the end of the drafting rolls, and showing the roll stand in which they are supported;

Fig. 2 is a perspective view of the drafting mechanism with parts removed for clarification;

Fig. 3 is a perspective view of the middle and forward drafting elements with parts broken away and removed to better show the position and operation of the endless belts;

Fig. 4 is a perspective view showing one position assumed by one of the rolls as it is being lifted from the machine for the removal of the belt from position;

Fig. 5 is an elevational view of the three elements which operate to drive the belt;

Fig. 6 is a sectional view on the line 6—6 of Fig. 5 with the upper roll omitted;

Fig. 7 is a view similar to Fig. 5 with the belt in position and showing the manner of pivoting the take-up device for the belt;

Fig. 8 is a perspective view showing the underneath side of the belt guide member;

Fig. 9 is a perspective view of one of the cradle members;

Fig. 10 is an elevation of the cradle roll alone.

In long draft spinning, the use of a belt or apron as a conveyor or carrier for yarn from the nip of one pair of drafting elements to the other, is extensively used. Usually this belt is endless and embraces within its loop one or more rolls about which it is drawn with sufficient tension so that the embraced roll will drive the belt. The same integral piece of shaft which forms such driving roll extends through a large number of such belts and drives them and should it become necessary to replace any belt, this is done by positioning a strip of belt material about the rolls which it is to embrace and then cementing its ends together. About twenty minutes is required for such cemented belt ends to dry, and during this length of time the spinning frame is entirely out of operation. The belt system which we have devised and disclosed herein does not depend upon the belt being drawn tightly about some rotating member or drive but is rather nipped at two spaced points for its driving action; and we have so arranged the roll or drafting element which is embraced within the loop of the endless belt that it may be lifted from position in the same manner that the usual top roll of a spinning frame is lifted from position, whereby the endless belt may be readily removed or an endless belt may be positioned in the frame without the necessity of cementing its ends and waiting for the same to dry, thus eliminating the idleness of a frame for the length of time which is required for such cement to dry; and we accomplish this by driving the belt on its work-contacting surface and providing a take-up for the slack of the belt which in no way functions as a tensioning device for the work-engaging run of the belt; and the following is a more detailed description of the present embodiment of this

30

invention, illustrating the preferred means by which we obtain these advantageous results.

With reference to the drawings, the roll stands 10, 10' are of identical structure and are spaced 5 apart on a suitable support of the frame the usual distance to receive the elongated sections of the bottom rolls which are keyed together in a usual manner to transmit their drive along each side of the frame. Each roll stand is provided 10 with a base portion as 11, 11', a standard portion as 12, 12', and a body portion as 13, 13'. Each also has bearing recesses as 14 and 15 for the lower front and lower back rolls and a recess 16 for a driving member which is located below a 15 line between the bearing portions 14 and 15.

The lower front roll 17 and the lower back roll 18 are each of a single piece of material extending from one roll stand 10 to the next roll stand 10' with fluted portions 20 at intervals along its length 20 separated by smooth portions 21 of a less diameter therebetween. The end portions of this roll 17 are reduced as at 22, 22' to fit the bearings 14, which reductions provide shoulders as 23 engaging the edges of the body portions of the stands 25 to prevent endwise sliding of the roll therein.

The lower back roll 18 is similarly fluted as at 24 at intervals with the smooth spacing portions 25 of less diameter between. Its end portions are reduced as at 26, 26' to fit the bearings 15, which 30 reductions provide shoulders as 27 to engage the edges of the bodies of the stands and prevent endwise movement of the roll 26 in its bearings.

A driving member designated generally 30 like the said lower rolls, also consists of an elongated 35 portion of a single piece of material having fluted portions 31 at spaced intervals along its length, while its ends are reduced as at 32 to be received within the bearings 16 and provide shoulders 33 for engaging with the ends of the bearing recess 40 for the prevention of endwise movement of the member in its bearings. The fluted portions 20, 24 and 31 are arranged in rows opposite each 45 other in which position the portion 31 is disposed below the level of the others. Located in alternate spaces between the fluted portions 31 there is an enlarged fluted portion or hub 34 which is slightly larger than the diameter of the fluted portion 31 for purposes to presently appear. The driving member 30 is located below the line of 50 travel of the yarn, which is tangent to the upper surfaces of the fluted portions 20 and 24 of the front and back rolls, a sufficient distance so that an additional roll may be placed on top of the member 30 and its upper surface be substantially 55 in this line of travel of the yarn.

The cap frame consisting of a rod 35 pivoted in the recess 36, 36' of the roll stand is provided 60 with forwardly extending arms 37 rigidly secured thereto which are located over some of the spaces 21, 25 such as at every second occurrence. The end arms 37 of the cap frame rest upon the fin 38 extending upwardly from the bearing 14 and as the intermediate arm 37 is fixed to the rod 35 it is supported through this rod. The arms 37 65 are in close proximity to the lower rolls 17 and 18 and vertically extending channels 39 and 40 are provided in the arms or in opposite sides thereof as at 39, 39' of the intermediate arm and which extend throughout the entire depth 70 of the arms, these channels are located above the lower rolls 17 and 18. At a point intermediate these channels 39 and 40 the arms are thickened as at 41 to extend into closer proximity to the drive member 30 and vertical channels 42, or 75 in the middle arm 42, 42', are formed in these

thickened portions and extend throughout the entire depth of the arms at a location above the driving member 30. These channels form guides for removable rolls such as the upper back roll 44, and the upper front roll designated generally 45, 5 and the belt rolls which will be more fully described.

The upper leather covered back roll 44 has 10 trunnions 46 to fit within the channel 39 and consists of spaced sections 47, 47 to rest upon the fluted sections 24, 24 beneath, while the space 48 between these sections 47 is for the reception of one end of the saddle of the weighting member which will be hereinafter more fully described.

The upper leather covered front roll 45 has 15 trunnions 49 fitting within the channel 40 with spaced sections 50, 50 resting upon the fluted sections 20, 20 of the lower front roll with a space 51 between also for the reception of the saddle of the weighting means. In the channels 42, 42' 20 there is first positioned the trunnions 53 of the roll 54 fluted throughout its length which is of the same length as the top rolls, this roll 54 becomes the bottom roll of the intermediate pair of drafting elements and is smaller than the 25 driving member 30 an amount sufficient to drive the belt to be later described, faster at one nip than the other, an amount found satisfactory being about ten thousandths of an inch smaller in diameter. There is then positioned in these same 30 channels 42, 42' the trunnion 56 of the upper leather covered roll 57 having sections 58 with spaced portion 59 between these sections, which spaced portions receive one end of the saddle of a weighting means, to be more fully described. 35 This roll 57 is the top roll of the intermediate pair of drafting elements and is the same in all substantial respects as the upper rolls 44, 45 of the back and front pairs of drafting elements previously described.

A pair of endless belts or aprons 60 are positioned about the fluted roll 54 each of which belts receives within its loop this lower fluted roll 54, one portion of the belt being positioned above and in contact with each fluted portion 31 of 45 the driving member 30 so that the travel of the belt is above the fluted portion 31 and between this portion and the lower roll 54, while the other portion of the belt on the top of the lower roll 54 is between it and the section 58 of the upper 50 roll 57.

The hub portion 34 between the portion 31 of the member 30 is of a diameter a little greater than the diameter of the fluted portion 31 plus the thickness of the belt so as to be just engaging 55 with the fluted portion of the lower roll 54 to thus effect a positive driving connection between the drive member 30 and the lower intermediate roll 54. This positive drive while desirable is not necessary as satisfactory results may be obtained 60 without it and of course where not used the hubs 34 will be omitted and smooth plain portions exist in their place, likewise the fluting need not extend the full length of the roll 54 but the same be formed as are the other lower rolls except in 65 short sections of the length of the present roll 54 shown.

A belt guide member 61 of reduced forward dimension as at 62 so as to reach further towards the bight between the lower roll 17 and the upper 70 roll 45 is hinged by a single pin 63 to an arm 37 of the cap frame so that the member 61 is supported at only one end while being free to rock upwardly about the pin 63. Its movement is limited in a downward direction by reason of its be- 75

ing located in a recess 67 so that its rear lower edge 65 will contact the abutment 66 formed by the edge of the recess. This member 61 is grooved as at 64 to receive the belt in the groove.

5 The belt 60 extends forwardly from the nip between the rolls 57 and 54 about the forward reduced edge 62 of the guide member 61 forming the working run 68 of the belt. From thence the belt passes rearwardly beneath the guide 61 and 10 between the nip of the roll 54 and the driving member 30. As the diameter of the roll 54 is smaller than that of the member 30, then as the driving member 30 rotates it tends to pull the belt in the direction of the arrow 69, see Fig. 1. 15 faster than it is pushed forward by reason of the nip between the rolls 57 and 54, thereby exerting a tension on the forward run 68 of the belt, although it is driven at two points along its length.

Between the nip of drive member 30 and the 20 roll 54 and the nip of the rolls 54 and 57 the belt 60 extends rearwardly and somewhat downwardly at an angle in a loop 71 which, in order to prevent buckling, is conveniently guided by any 25 suitable device. The angle of the belt is such as to catch the work 110 which may drop onto the belt and feed it forward to the middle nip elements. For convenience we utilize a cradle designated generally 75 consisting of side plates 76 with an integral connection 77 between them, 30 which is conveniently formed by bending up a single piece of sheet stock. Side plates 76 serve to guide the belt between them and are notched as at 78 to receive drive shaft 30 and are notched as at 79 to receive the trunnions 80 of the roll 35 81 about which the looped portion 71 of the belt 60 passes the belt supporting the weight of the roll 81 which is free in said notches 79 to rise or lower to conform to the travel of the belt. The roll 81 is tapered from its middle toward its ends 40 to guide the belt as it travels about this roll and maintains it central of the cradle. The length of the belt is such that the cradle 75 is positioned at an angle to the vertical, thus the roll 81 and weight of the cradle tends to swing 45 the cradle about the drive shaft 30 as a pivot and will take up any slack which may occur and guide and keep the belt traveling in the desired direction and yet the cradle is free to rise and relieve any undue tension should such 50 occur. The lower roll 54 is so positioned that when the belt 60 is thereabout the upper surface of the run 68 of the belt is in the common line for the drafting of the fibers between the nips of the back pair of drafting elements and front 55 pair of drafting elements which is substantially in the plane of a common tangent to the top of the lower front and back rolls 17 and 18.

The upper roll of each pair of drafting elements is weighted. A saddle 85 engages the portion 60 48 of the upper back roll and the portion 59 of the middle upper roll; while a saddle 86 engages the portion 51 of the upper front roll and also seats in a recess or fork 87 on the saddle 85. A link 88 embracing the saddle 86 to exert a pull 65 thereon extends downwardly between the rolls to be engaged by the usual lever 89 pivoted in the link 90 which is adjusted as at 91, the lever being loaded as at 92, either by a spring or having a gravity actuated member suspended therefrom.

70 The drive of the back pair of rolls and front pair of rolls will occur in the usual manner, while the shaft 30 for the intermediate drafting elements will be driven from the back or front rolls in a manner similar to the known drive of an intermediate lower roll; in this case, however,

the shaft 30 will be dropped down to the new position. The drive of the belt consisting of the intermediate drafting elements has been above indicated.

75 The rolls 54 and 57 are urged downwardly by their own weight and also through the weighted saddle mechanism toward the drive shaft 30. The belt extending between member 30 to roll 54 and also between roll 54 and roll 57, has such pressure transmitted through it and is firmly 10 nipped. Rotation of the drive member 30 will through friction and also positively as by means of hub 34 transmit motion to the lower intermediate roll 54 and this roll in turn will transmit motion through friction to the upper intermediate roll 57, thus effectively nipping and feeding the belt 60 in its travel.

Should it be required to replace one of the 15 belts or aprons, it is merely necessary to remove the weighting mechanism in the usual manner, 20 lift out the upper intermediate roll 57, remove the take-up cradle 75 by unhooking it at its notches 78 from the drive shaft 30 and then removing the roll 81 from the cradle and entirely 25 freeing this bight of the belt, such as shown in Fig. 4. Next the lower roll 54 may be lifted upwardly from its notches 42, 42' (see Fig. 2) in a manner similar to that shown in Fig. 4 (note the full showing of notch 42' from which the roll 30 54 is lifted), and by endwise movement the roll 30 54 is withdrawn from the belts. The belts then are only encircling the front guide 62 and may be moved to the position shown in dot-dash lines in Fig. 2 and readily slid off one end thereof. A fresh endless belt may be positioned in the 35 frame by merely reversing the steps just described; thus, it becomes unnecessary to piece up any belt which has heretofore been a major operation in the fixing of a belt in a spinning frame. Further, it is merely necessary to feed 40 the roving 110 to the back rolls and by its dropping onto the belt, as shown in Fig. 1 it is fed through the middle pair of nipping elements.

In some instances where a fourth line roll is 45 desired, the same may be positioned as shown in Fig. 1 as at 100 with its trunnions engaging suitable formations 101, as shown in Fig. 2, in the arms 37. Support is obtained through the guide member 61 which guides the forward end of the belt. Its motion is derived from contact with the belt and it has a slip engagement with the 50 yarn by reason of its not being weighted.

While we have spoken of certain sections of the rolls as being fluted, it will be readily understood that any means of roughening the rolls may 55 be used, such as sand blasting, knurling or any way of increasing the friction. By reason of the guide 61 being hinged it may be readily turned up for removing the belt and for ease of positioning a new belt thereon; while this guide 60 member will also lift up by reason of its hinge connection if there is any undue accumulation of lint upon the apron and which might otherwise jam at its close proximity to the lower front roll 17, whereby any breakage in the mechanism 65 would be prevented. Also, the cap frame as a whole may lift to a limited extent to relieve any congestion. The cap frame may be freely lifted by using the horns 103 after the weighting mechanism and the cradles are removed.

70 The foregoing description is directed solely towards the construction illustrated, but we desire it to be understood that we reserve the privilege of resorting to all the mechanical changes to which the device is susceptible, the invention be- 75

ing defined and limited only by the terms of the appended claims.

We claim:

5. In a drawing mechanism for spinning frames, pairs of drafting elements including relatively short removable upper roll sections in each pair, one of said pairs also having a similar relatively short removable lower roll section, an endless belt embracing within its loop said removable
10. lower roll section, a pivotally arranged guide adjacent the bight of another pair of drafting elements and adapted for swinging movement toward or away from the same, a run of said belt extending over said guide, said guide being supported at one end only whereby the belt may be inserted thereover while in endless form.
15. 2. In a drawing mechanism for spinning frames, pairs of drafting elements including relatively short removable upper roll sections in each pair, one of said pairs also having a similar relatively short removable lower roll section, an endless belt embracing within its loop said removable lower roll section, and a guide adjacent the bight of another pair of drafting elements, a run of said belt extending over said guide, said guide being hinged to swing upwardly for ease in positioning the belt thereover.
20. 3. In a drawing mechanism for textile slivers or rovings, two pairs of drafting elements, each pair consisting of upper and lower removable rolls, an endless belt passing between one pair of rolls inclosing the lower roll thereof and having a run extending forward toward the bight of the other pair of rolls, a pivoted guide supported at one end only extending in cross-wise relation of said belt for internally guiding the front loop of the belt, said guide being arranged to swing upwardly to enable positioning of the belt thereover, means for tensioning said belt, and means in driving engagement with said belt inclosed lower roll to rotate the same for driving the belt.
25. 4. In a drawing mechanism for textile slivers or rovings, two pairs of drafting elements, each pair of which consists of upper and lower removable rolls, an endless belt passing between one pair of rolls inclosing the lower roll thereof and having a run extending forward toward the bight of the other pair of rolls, a driving member beneath said belt inclosed lower roll having engagement therewith for driving the same, a guide extending in cross-wise relation to said belt for internally guiding the front loop of the belt, said guide being hingedly mounted for movement to a second position to enable ready positioning of the belt thereover, an extended loop portion of the belt back of said belt inclosed roll extending rearwardly and downwardly from the rolls between which it passes, a cradle pivoted on said driving member to swing on the same with free movement by gravity, and means carried by said cradle effective to tension said belt and adapted for internally guiding the rear loop thereof.

5. In a drawing mechanism for textile fibers, two pairs of drafting elements, each pair consisting of upper and lower removable rolls, a belt passing between one pair of rolls inclosing the lower roll thereof, and having a run extending forward toward the bight of the other pair of rolls, a driving member beneath said belt inclosed lower roll having driving engagement therewith for driving the same, a guide extending in cross-wise relation to said belt for internally guiding the front loop thereof, said guide member being hingedly mounted for movement to and from a second position to enable ready positioning of the belt thereover, an extended loop portion of the belt back of said belt inclosed roll extending rearwardly and downwardly from the rolls between which it passes, a removable cradle pivoted at one end on said driving member for free swinging movement about the same by the action of gravity, and a roll removably mounted in said cradle at the other end thereof for internally guiding the rear loop of said belt, the length of said belt being such as to dispose said cradle at an angle to the vertical whereby the action of gravity on the roll, cradle and belt is effective to take up the slack in the belt.

6. In a drawing mechanism for textile fibers having a pair of drawing rolls and an endless belt for conducting the fibers thereto, the combination of a roll driving said belt and inclosed by the same, a rotatable member having driving engagement with said belt inclosed roll for driving the same, a guide member for internally guiding the front loop of said belt, said guide being positioned adjacent said drawing rolls and supported at one end only for pivotal movement to be turned from a guiding position for the belt into a second position whereby the belt may be either inserted on or removed from the guide over the free end thereof while in endless form, a guide roll for internally guiding the rear loop of said belt, said guide roll being mounted to rotate about a substantially fixed axis well spaced below and relatively remote from the path of travel of the textile fibers, and a supporting frame for said guide roll pivoted at one end portion on said rotatable driving member to swing about the same with free movement by the influence of gravity for maintaining said belt taut.

7. In a drawing mechanism, upper and lower drafting elements, each of said elements comprising a relatively short removable roll member, an endless belt having within its complete loop said lower drafting element, and a movable guide member for guiding the forward loop of said belt, said guide being supported at one end only and hinged to swing upwardly for ease in positioning the belt when in endless form.

EDWARD L. MARTIN.

JOHN FREDERICK JACKSON.
